TOOTHPRUSH HOLDER

Harland S. Spears, Lindsay, Calif.

Application March 14, 1947, Serial No. 734,689

1 Claim. (Cl. 206—15.1)

1

This invention relates to an improved construction of holder for toothbrushes and more especially to a holder of extremely simple construction to which a toothbrush may be quickly and easily applied or removed and which will effectively function to contain the toothbrush in a sanitary manner and so as to prevent distortion of the bristles.

More particularly, it is an object of the invention to provide a readily demountable holder for detachably containing a toothbrush and having means to permit the free circulation of air therethrough for facilitating the drying of the bristles and while the toothbrush is contained by the holder with the bristles in a normal position to prevent distorting thereof during drying.

Various other objects and advantages of the invention will hereinafter become more fully apparent from the following description of the drawing, illustrating preferred embodiments thereof, and wherein:

Figure 1 is a side elevational view, partly in section, showing the preferred embodiment of the invention;

Figure 2 is a longitudinal sectional view taken substantially along a plane as indicated by the line 2—2 of Figure 1;

Figures 3 and 4 are cross sectional views of the holder taken substantially along planes as indicated by the lines 3—3 and 4—4, respectively, of Figure 1;

Figure 5 is a sectional view of one section of the holder and showing a toothbrush disposed therein and in the course of being removed therefrom;

Figure 6 is a longitudinal sectional view of the lower portion of a slightly modified form of the bottom section of the holder;

Figure 7 is a fragmentary side elevational view, partly in vertical section, illustrating a modified form of the holder, and

Figure 8 is a cross sectional view thereof taken substantially along a plane as indicated by the line 8—8 of Figure 7.

Referring more specifically to the drawing, and first with reference to Figures 1 and 2, 10 designates generally a rack including an upright bar 11 through which one or more driven fastenings 12 loosely extend for securing the rack 10 to a suitable upright supporting surface, not shown, such as a bathroom or lavatory wall. The bar 11 is provided adjacent its lower end with an outwardly projecting shelf 13 having one or more openings 14 extending perpendicularly there-

through, for a purpose which will hereinafter become apparent. The upper end of the bar 11 is curved outwardly over the shelf 13 to form a hood 15 having a recessed underside, as indicated in dotted lines at 16 and which may form a reflector for an ultra-violet ray lamp bulb 17 contained in an electric socket 18 which is connected to a suitable source of electric current, not shown, by the wiring 19 and which is contained in the recessed portion 16 of the hood 15 and substantially directly above the opening 14, all for a purpose which will hereinafter become apparent.

Referring to Figures 1 to 5, inclusive, a toothbrush holder, designated generally 20, comprises an upper or head section 21 and a lower base section 22. The base section 22 tapers toward its lower end which is closed except for a plurality of small perforations 23. The enlarged upper end of the section 22 terminates in a flared open top 24 which is preferably oval in cross section, as seen in Figure 3, but which may be circular, which will hereinafter become apparent. The remainder of the bottom section 22 may be circular in cross section, as seen in Figure 4, and likewise may be oval in cross section.

The upper or head section 21 is preferably oval in cross section and is provided with an externally convex upper end or dome 25 which is provided with fine perforations 26, as seen in Figures 1 and 5. The upper section or head 21 has a rounded bottom 27 which is adapted to fit snugly in the flared upper end 24 of the section 22 and which is provided with a restricted opening 28 to permit the passage therethrough of the head 29 of a toothbrush 30.

The opening 14 of the shelf 13 is sized to readily receive the perforated lower end 23 of the section 22 and the taper of said section is such that it will bind in the opening 14, substantially intermediate of the ends thereof for thereby supporting the holder 20 therein, as illustrated in Figure 1. Accordingly, it will be readily apparent that the holder section 22 may be readily lifted out of the opening 14 and that the shelf 13, by means of said opening 14, will afford means for demountably supporting the holder 20 by engagement with the base section 22. The upper section or head 21 seats with its rounded bottom 27 in the flared open end 24 and be retained thereby in assembled position on the lower section 22; however, the head 21 may be provided with one or more spring clips 31 secured 55 at their upper ends externally thereto and dis-

posed longitudinally thereof for resilient frictional engagement over portions of the outer side of the flared end 24 for providing connecting means between the holder sections. As clearly illustrated in Figure 1, the lower free ends of the clips 31 are flared outwardly sufficiently to engage externally of the rim or upper edge of the portion 24 to pass thereover when the head 21 is applied to the base section 22.

The opening 28 in the bottom 27 is sized to permit the toothbrush head 29 to pass therethrough by distortion of the bristles thereof and said bristles are sufficiently rigid to retain the head 29 therein until forceably withdrawn therefrom through the opening 28. The lower or base section 22 is of such a length as to receive the handle of the toothbrush 30 therein when the head 21, containing the toothbrush head 29, is applied to the base section 22, as previously described. With holder 20 in its fully assembled position, as seen in Figure 1, the toothbrush 30 contained therein is of such a length that the handle end of the toothbrush will engage the perforated bottom 23 for holding the brush head 29 elevated in the head 21, as seen in Figure 1, and so that the bristles of the brush head will not be distorted by engagement with the rounded bottom 27.

The perforations 23 and 25 permit a free passage of air through the holder 20 to facilitate drying of the bristles of the head 29 but are sufficiently fine to exclude insects and substantially all dirt and impurities from the interior of the holder.

At least the head or upper section 21 is formed of a material which will permit the passage therethrough of the germicidal rays from the ultraviolet lamp bulb 17 for sterilizing the brush head 29, especially the bristles thereof, and if desired, the entire holder may be formed of a transparent material.

Figure 6 illustrates a slightly modified form of the lower end of the bottom or base section, designated 22a and wherein the perforated bottom is provided with an axial threaded opening 32 for a feed screw 33 which extends therethrough and the upper end of which turnably engages a false bottom or follower 34 which is adapted to support the handle end of the toothbrush 30. The screw 33 is provided with a knob 35 on its lower, outer end by means of which it can be manually adjusted for raising and lowering the false bottom or follower 34 for accommodating toothbrush handles of various lengths and for supporting the brush head thereof correctly positioned in the holder head 21, as previously described and as illustrated in Figure 1.

Figures 7 and 8 illustrate a slightly modified construction of holder, designated generally 20b and comprising the upper and lower sections 21b and 22b, respectively, which were shown as being circular in cross section. Section 22b is provided with a circular open flared end 24b for receiving the circular rounded bottom 27b of the head 21b. The head 21b, above and adjacent its rounded bottom 27b, is provided with an externally disposed circumferentially extending bead 36, portions of which are adapted to engage in spring clips 37 which project from the upper edge of the flared end 24b for resiliently and frictionally retaining the holder sections 21b and 22b assembled.

Various other modifications and changes are contemplated and may obviously be resorted to, without departing from the spirit or scope of the invention as hereinafter defined by the appended claim.

I claim as my invention:

A toothbrush holder comprising detachably connected upper and lower holder sections for containing a toothbrush, said upper section having a lower end receivable in the upper end of the lower section and provided with a restricted opening sized to permit the forceable passage of a toothbrush head therethrough, said upper section being sized to loosely contain the toothbrush head, a platform loosely disposed in the lower part of the lower section for supporting the handle end of the toothbrush, the restricted opening of said upper section engaging the neck of the toothbrush handle beneath and adjacent the brush head for cooperating with the platform to support the brush head within the upper section and with its bristles out of contact therewith, and a feed screw connected to the platform and extending threaded through the lower end of the lower section for adjustably positioning the platform longitudinally of the holder to accommodate toothbrushes of different lengths.
